EXCAVATING APPARATUS

Edward H. Kluckhohn, Naperville, Ill.

Application October 7, 1944, Serial No. 557,571

9 Claims. (Cl. 214—137)

1

This invention relates to improvements in excavating machinery and apparatus and to a novel form of bucket for use therewith and its purpose is to provide forms of buckets and apparatus which will permit digging, excavating and moving operations to be carried on in a new and improved manner and more economically than has heretofore been possible.

Many forms of excavating apparatus, employing buckets of the clam-shell or the shovel types have heretofore been in common use in carrying on various digging, excavating, earth moving and loading operations but the uses to which such apparatus could be put have been unduly restricted. These limitations have been imposed to a considerable extent by the forms of buckets which have been used. A bucket of the well-known clam shell type is capable of use only in elevating and loading or unloading loose materials such as sand, gravel, loose earth, crushed rock and the like, and it has the further disadvantage that there is considerable leakage therefrom and consequent waste or damage. While a bucket of the usual shovel type is capable of use for digging purposes, such a bucket has also had the disadvantage of leakage when used for conveying purposes and, in addition, its uses have been limited because it has had only one cutting edge and because it has always had a fixed pitch or inclination which was not always in line with its direction of movement during the digging operation so that its use has not been efficient and has required the expenditure of an undue amount of power. A further disadvantage of prior excavating apparatus has been that whether the bucket was of the clam shell or the bucket type the entire contents of the bucket had to be dumped in one operation.

The principal object of the present invention is to provide improved excavating apparatus including an improved bucket having double cutting edges so that it may be moved in either of two directions in effecting digging or cutting operations, thus providing means for carrying on a variety of operations which have not heretofore been possible with excavating machinery. A further object is to provide a bucket having double cutting edges in combination with controlling means for varying the inclination or pitch of the bucket so that the cutting force will at all times be applied in the plane of a cutting edge. Another object is to provide a combined digging and conveying bucket which will be free from leakage. Another object is to provide a digging bucket in combination with actuating means for controlling the movements and pitch of the

bucket so that the contents of the bucket may be discharged gradually or intermittently in accordance with the will of the operator. Still another object of the invention is to provide a bucket, provided preferably with double cutting edges, and arranged for pivotal mounting with all of the pivotal connections located inside of the planes of the lateral faces of the bucket so that the bucket may be used to cut excavations having square corners.

A further object of the invention is to provide improved excavating apparatus of the shovel, hoe, bulldozer, overhead shovel and dragline types in which the improved double-edged digging bucket is actuated in an improved manner to have cutting action upon movement in either of two directions, so that some form of the apparatus may be used efficiently for various purposes such as the digging of excavations having horizontal floors and vertical side walls, digging canals and tunnels and removing the rock and earth therefrom, building elevated roadbeds, grading roadways and moving earth in position, and loading and unloading various loose materials such as earth, sand, gravel and the like. These and other objects of the invention will appear more clearly hereinafter.

The nature of the invention will be understood from the following specification taken with the accompanying drawings in which several embodiments are illustrated.

In the drawings,

Figure 1 shows a perspective view of one form of the improved digging bucket which is provided with double cutting edges;

Fig. 2 shows a somewhat diagrammatic side elevation of a shovel embodying the improved features of the present invention, including the double-edged cutting bucket, illustrating the use of a shovel in moving the bucket in either of two directions for digging purposes in the process of forming an excavation having a vertical side wall, where the principal parts of the shovel are located on the floor of the excavation, the bucket being actuated by fluid pressure means for turning it about its own axis;

Fig. 3 shows a partial side elevation of gear and chain mechanism which may be used in turning the bucket on its axis in place of the fluid pressure means shown in Fig. 2;

Fig. 4 shows a partial side elevation of still another form of mechanism wherein the bucket may be turned about its own axis by the use of cables;

Fig. 5 shows an elevation of excavating ap-

2

paratus embodying the present invention when constructed in the form of a hoe which is shown as being mounted on the surface of the ground and being employed in forming an excavation at a lower level having vertical side walls, the use of the bucket in cutting the earth upon movement thereof in either vertical direction and also horizontally being shown by dotted lines;

Fig. 6 shows a side elevation of a bulldozer embodying the features of the present invention, the use of the bulldozer in effecting pushing, conveying and dumping operations being illustrated by dotted lines;

Fig. 7 shows a side elevation of an overhead shovel embodying the features of the present invention, the use of the bucket in digging, elevating, conveying and dumping being shown by dotted lines;

Fig. 8 shows an elevation of excavating apparatus of the dragline type, the various positions which may be assumed by the double-edged cutting bucket in excavating, conveying and dumping operations being shown by dotted lines;

Fig. 9 shows an end elevation of a modified form of the improved bucket in which the pivotal connections are located inwardly from the end faces of the bucket so that it may be employed in forming an excavation having upright walls and square corners; and

Fig. 10 shows a side elevation of a modified form of bucket illustrated in Fig. 9.

In Fig. 1 of the drawings there is shown a perspective view of the improved digging bucket 15 which comprises a curved wall 15^a rigidly and continuously united at its ends with parallel end walls 15^b to form a fluidtight receptacle. The curved wall 15^a is formed of hardened steel at its longitudinal parallel edges 15^c which are sharpened to form the cutting edges of the bucket and the end walls 15^b are so shaped at their margins that they project outwardly in conformity with the projection of the cutting edges 15^c. The end walls 15^b are provided with apertures 15^d through which pivotal connections are made with the supporting and operating parts by which the bucket is moved about its own axis. By this construction, there is provided a digging bucket which may be used to effect cutting operations upon movement thereof in either of two directions and the cavity of the bucket between the cutting edges is sufficiently concave to permit the bucket to be used for conveying purposes without danger of spilling its contents and without danger of leakage. By properly controlling the position of the bucket with respect to its pivots, the cutting edges may always be located in the desired planes and the force which is applied for cutting purposes may be applied in the plane of the cutting edge which is in use. By controlling the movement of the bucket about its own pivots, the discharge of the contents of the bucket may be made to take place gradually or intermittently, as the operator may desire.

The embodiment of the double-edged digging bucket of the type described above in an excavating apparatus of the form known as a shovel is illustrated in Fig. 2. The frame 16 of this apparatus is mounted for rotation about a vertical axis on a chassis 17 which is carried by the usual Caterpillar tractor tread mechanism 18. In this instance, the treads are shown mounted upon the floor 19^a of an excavation 19 having a vertical wall 19^b formed by cutting away the body of earth 20. Mounted on the frame 16, there is a power plant 21 adapted to generate steam for

operating the piston within a cylinder 22. This piston is connected by a connecting rod 23 with a disk 24 mounted on the shaft which also carries a pinion 25 arranged to mesh with a gear 26. This gear is mounted on a drum shaft 27 carrying a pair of cable drums 28 and the gear also meshes with an idler pinion 29 through which there is driven another gear 30 fixed on a gear shaft 31 which has fixed thereon a sprocket gear 32. These cable drums, thus actuated through the steam cylinder 22, are capable of operating the excavating apparatus hereinafter described and the power plant 21 may also be employed to provide power for operating the tractor treads 18 by which the shovel is moved from one position to another.

On the forward end of the frame 16, there is mounted a bracket 34 having pivotally mounted thereon a boom 35 which extends upwardly and toward the right as viewed in Fig. 2 and which carries at its upper end a bracket 36 having pivotally attached thereto an arm 37. This arm carries at its lower end pulleys 38 adapted to be engaged by a cable 39 which has one end attached to a member 40 secured to the shaft 41 of pulleys 42. The shaft 41 is journaled in bearing brackets 43 mounted upon the upper frame structure 16^a and the end of the cable 39, opposite the end which is attached to the member 40, after being passed over one of the pulleys 42, is wound about and secured to one of the drums 28 so that, upon actuation of the steam cylinder 22, the drum 28 attached to the cable 29 may be operated for shortening or extending the stretches of cable between the pulleys 38 and the pulleys 42, thereby raising or lowering the boom 35 about its pivot on the bracket 34.

At an intermediate point on the boom 35 there is pivotally mounted a bracket 44 which carries a pair of sticks 45 which straddle the boom 35 and upon the free ends of which the digging bucket 47 is pivotally mounted. The ends of the sticks 45 are attached to pivot pins 48 engaging apertures in the end walls of the bucket and secured thereto so that upon rotation thereof the bucket is turned about its axis. One of these pivot pins 48 is secured to a disk 49 which has a pivotal eccentric connection with a connecting rod 50 operated by a cross head 51 attached to a piston rod leading from the cylinder 52, carried by one of the sticks, to which an operating fluid, such as steam or compressed air, is admitted through a flexible conduit 53 extending from the power plant 21 or from an air compressor mounted on the frame 16. Upon admission of steam or the like to the cylinder 52, the bucket 47 may be rotated about its own axis, through more or less than a complete revolution, and, with the other parts in proper positions, may be made to assume the various positions which are illustrated by dotted lines.

The pivot pins 48 are also attached to a U-shaped bracket 55 which is pivoted at 56 through a frame 57 carrying a pulley 58. A cable 60 is attached to the frame 57 and, after extending around one of a series of pulleys 61 carried by the bracket 36, is passed around the pulley 58 and then over another of the pulleys 61 from which it extends downwardly and is wound about and secured to the other drum 28. Thus, upon the winding of the last-mentioned drum, the effective length of the portions of the cable 60 extending between the frame 57 and the pulleys 61 may be shortened in order to raise the bucket 47 about the pivot formed by the mounting of the

sticks 45 on the pivoted bracket 44. By operating the cable 60, the sticks 45 may be swung toward or away from the boom 35 in order to vary the position of the bucket 47 with respect to the free end of the boom.

It will thus be apparent that by operating the above-described mechanism, all of which is controlled from a position within the operator's cabin on the frame 16, the boom may be raised or lowered, the sticks moved toward or away from the boom, and the bucket rotated freely on the ends of the sticks. By means of these operating adjustments, the bucket 47 may be caused to assume the inverted position shown by full lines in Fig. 2, which position it would occupy when the contents thereof are to be dumped in one operation. In the positions shown by dotted lines at 47^a, the bucket is in its upright position which it would occupy when materials are being conveyed thereby from one position to another and it will be apparent that by a combination of the above-described adjustments, coupled with the rotation of the frame 16 about its vertical axis on the chassis 17, the loaded bucket may be moved to any position within a wide range to permit the discharge of its contents. In the position shown by dotted lines at 47^b, the bucket is partially inverted with one of its cutting edges extending vertically for movement in a vertical plane, which movement it might have when cutting the vertical wall shown at 19^b. In the position shown at 47^c, the bucket has been partially reversed in its position and the opposite cutting edge is directed horizontally along the floor 19^c of the excavation. When in this position the bucket may be moved horizontally by the proper movement of the boom 35 and the sticks 45 in order to effect a horizontal cutting action and a resulting filling of the bucket and the same movement may be employed for filling purposes only. In the position shown at 47^d, the bucket is also arranged with one cutting edge extending horizontally but is located in a position which would precede that shown at 47^c in the operation of filling the bucket. When the bucket has been filled and elevated and moved to the place where the discharge is to take place, it will be apparent that it may be rotated about its own axis to any desired degree in order to cause the discharge to take place all at one time or in an intermittent or gradual fashion.

The sprocket gear 32 shown in Fig. 2 is connected by a sprocket chain 65 with a sprocket gear 66 mounted on a shaft journaled in bearings carried by the lower part of the boom 35. This shaft carries another sprocket gear which meshes with an endless chain 67 arranged to extend upwardly along the boom and to drive a sprocket gear 68 mounted on the pivot of the bracket 44. This driving chain connection need not be employed when the bucket 47 is turned by the use of fluid pressure as shown in Fig. 2 but this chain connection may be used to drive a sprocket chain 70, shown in Fig. 3, which may be mounted on one side of the stick 45 to actuate a sprocket gear 71 mounted upon one of the pivots of the bucket, as illustrated in Fig. 3. Also, the chain drive may be used to actuate a grooved pulley 73, shown in Fig. 4, which drives a belt 74 mounted to extend around a grooved pulley 75 mounted on one of the pulleys of the bucket so that the bucket may be turned about its own axis in the manner previously described.

In Fig. 5 of the drawings, the invention is shown as being embodied in excavating appa-

ratus of the hoe type in which the bucket is moved somewhat in the manner in which it is actuated in the shovel type of excavating machine described above, although the hoe is normally used on the surface of the ground for excavating at a lower level or for excavating a tunnel or the like along which the machine travels during the process of excavation. As illustrated in the drawings, the cabin 80 of the apparatus houses the usual power plant with power actuated drums for winding cables by which the bucket and associated apparatus are controlled. The cabin 80 is mounted for rotation about a vertical axis on a chassis 81 carried by the Caterpillar tractor treads 82 which, in turn, rest upon the surface 83^a of the earth 83. This apparatus is shown as being used in the excavation of a cellar, or the like, designated by the numeral 84, which has a bottom surface 84^a and vertical side walls 84^b.

On the forward end of the frame of this machine there is mounted a bracket 85 on which there is pivotally supported a boom 86 adapted to be swung in a vertical plane about its pivot and to be moved laterally when the cabin 80 and its supporting frame are moved about a vertical axis. A shovel 87 is pivotally mounted in a yoke carried on the free end of a stick 88 which is connected with a bracket 89 pivoted at the point 90 upon the outer or upper end of the boom. The bracket 89 extends upwardly above the stick 88 and a cable 91 connected to opposite ends of the stick serves to reinforce that member against downward bending. On one side of the yoke carried by the stick 88, there is mounted a cylinder 92 adapted to receive steam, compressed air or other actuating fluid through a flexible conduit 93 which extends rearwardly and along the boom 86 to the interior of the cabin 80. Upon actuation of a piston in this cylinder, a cross head 93 is moved in its guideway thereby operating a connecting rod 94 which is pivoted in an eccentric position on a disk 95 secured to the shaft or pivot pins of the bucket 87. Thus, by admitting compressed fluid to the cylinder 92, the disk 95 may be actuated to effect the rotation of the bucket about its own axis. As in the form of the invention previously described, this operation is under the control of the operator located in the cabin 80.

The digging bucket 87 is preferably of the form shown in Figs. 9 and 10 where it is illustrated as comprising a curved wall 87^a united at its ends with end walls 87^b which are recessed or offset inwardly to provide flanges 87^c having apertures 87^d therein which are engaged by the shaft or pivot pins upon which the bucket is rotatably mounted. The end faces 87^e of the bucket are thus displaced outwardly from the flanges 87^c through which the bucket is mounted on its supports and the operating connections are adapted to lie in this space within the planes of the end faces 87^e of the bucket so that when the apparatus is being employed for excavating a cavity having vertical side walls and square corners the bucket may be moved vertically for cutting one vertical wall and in contact with an adjacent right-angled wall without interference by the operating mechanism of the bucket. As in the previously described form of bucket, the bucket 87 has cutting edges 87^f and is so formed that it may be employed for conveying materials as well as for cutting them.

As shown in Fig. 5, a yoke 97 is connected to the outer end of the stick 88 and a cable 98 is

attached to this yoke and extends rearwardly through a sheave 99 to a point within the cabin 80 where it is wound on a power actuated drum. This drum may be operated as heretofore described in order to wind up or extend the cable in order to draw the bucket 87 downwardly toward the cabin or to permit it to be moved outwardly.

The outward swinging of the bucket 87 away from the cabin 80 is effected by a cable connection extending to the upper end of the stick 88 at which point the stick is shown as carrying a housing 100 in which are mounted pulleys 101 arranged to be engaged by a cable 102. This cable extends around pulleys 103 mounted on struts 104 and 105 carried by the frame on which the cabin 80 is mounted and, after passing around these pulleys 103, the cable 102 is extended into the cabin 80 and wound about and secured to a drum of the type heretofore described. Upon actuation of this drum by suitable power means, the cable 102 may be drawn inwardly in order to swing the stick 88 about its pivot 90 and thus move the bucket 87 upwardly and away from the cabin 80.

By means of the foregoing adjustments, it will be apparent that the bucket 87 may be caused to assume a variety of positions and to be moved in various ways for facilitating the digging of earth or other loose materials and the loading thereof into the bucket or the discharge of said materials from the bucket. In Fig. 5, the bucket 87 is shown in the normal suspended position which it would usually occupy when moving materials from one position to another. In the position shown at 87^a, by dotted lines, the bucket 87 is illustrated in the position which it occupied just before scooping up a quantity of the earth 83 from a point adjacent one of the vertical walls 84^b of the excavation. In the position shown by dotted lines at 87^b, the bucket is shown just after it has scooped up a quantity of this material and has been returned to the conveying position, such as that shown by full lines in the upper part of the figure. In the position shown by dotted lines at 87^c, the bucket is shown being moved vertically downward with one cutting edge arranged to travel along the vertical face 84^b of the excavation. In the position shown at 87^d, the bucket is shown with one cutting edge moving horizontally along the bottom surface 84^a of the excavation and in the position shown at 87^e the bucket occupies substantially the same position but has been moved further along the bottom surface 84^a. In the position shown at 87^f, the bucket is being moved vertically with one cutting edge traveling vertically along another vertical face 84^b of the excavation, and in the position at 87^g, the bucket is shown at the top of the excavation after it has been turned to a position to carry the materials which have been cut from the vertical face of the excavation during its vertical travel. In all of these operations, the same cutting edge of the bucket is shown as the operative edge engaging the materials to be excavated but it will be apparent that the operating mechanism of this hoe permits the bucket to be reversed in its position and to be moved downwardly and away from the cabin 80 during the excavating and loading process. Not only may the bucket be employed in the manner illustrated in the drawings to cut vertical sides and bottom walls of an excavation but it may also be used to cut the top wall of a tunnel or the like.

In Fig. 6 of the drawings, the invention is shown as being embodied in a bulldozer which is

substantially of standard construction except for the use therewith of the improved double-edged cutting bucket of the present invention. This bulldozer comprises a frame 105 carried by Caterpillar treads 106 which travel on the surface 107. At the sides of this machine, sticks 108 are pivotally mounted at the points 109 for vertical swinging movements about a horizontal axis. At the free ends of these sticks, there is mounted a shovel 110 which may be constructed according to the form of the invention illustrated in Fig. 1 or according to the form shown in Figs. 9 and 10. It has double cutting edges and is arranged to rotate about pivots 111 through the operation of a crank disk 112 which carries an eccentrically located pin 113 connected to a piston rod 114. This piston rod is connected to a piston mounted in a cylinder 115 which is pivoted at the point 116 on the side of the adjacent stick 108. A flexible conduit, not shown, extends from the cylinder 115 to a source of compressed fluid such as steam or compressed air located on the frame 105 and through this means the bucket 110 may be turned or rotated about its axis in order to bring either cutting edge into operative position or to turn the bucket for conveying purposes.

The sticks 108 are connected adjacent the forward end of the frame 105 through links 118 with the long arms 119 of bell crank levers 119. These bell crank levers are pivoted at the points 120 on the sides of the frame 105 and they have a short arm 119^b which is arranged to be actuated by a cylinder 122. This cylinder is pivoted at the point 123 on the frame of the machine and its piston is connected through a piston rod 124 with the short arm 119^b of the bell crank lever. Upon the admission of steam, compressed air or the like to the cylinder 122, at the left-hand end thereof as shown in Fig. 6, the bell crank levers 119 are swung about their pivots 120 to lower the sticks 108 so that they rest upon the stop members 125 which are extensions of the axles of the tread mechanism. Upon admitting compressed fluid to the right-hand end of the cylinder 122, as viewed in Fig. 6, the long arms 119^a of the bell crank levers are swung upwardly to elevate the sticks 108 so that the bucket 110 may then be elevated from the digging or scraping position shown at 110^a to the conveying position shown by the dotted lines at 110^b. As shown by dotted lines at 110^c, the bucket may then be rotated about its axis in order to dump its contents. By means of this form of the invention, the bucket may be used either to push materials along a predetermined surface 107 which is to be formed thereby or to pull said materials along said surface and, in either case, when a sufficient supply of such materials has been accumulated, the bucket may be turned about its axis in order to load said materials, whereupon the bulldozer may be made to travel to a suitable point where the contents of the bucket may be discharged.

The invention is shown in Fig. 7 of the drawings as being embodied in an overhead shovel which conforms substantially to the types of construction heretofore used except for the employment therewith of the double-edged bucket of the present invention. As there illustrated, the overhead shovel comprises a frame 130 carried by Caterpillar tractor treads 131 and comprising an upper frame structure 132. A pair of sticks 133 are pivoted at the points 134 on opposite sides of the frame 130 and the free ends of these sticks have pivotally mounted there-

between the bucket 135 which may be constructed either according to the form shown in Fig. 1 or according to the form shown in Figs. 9 and 10. The pivots 136 of this bucket are connected to a disk 137 carrying an eccentric pin 138 which is actuated by a connecting rod 138 connected to a cross head 140 which moves in guideways 141. This connecting rod is actuated by a piston rod 142 connected to a piston located in a cylinder 143 to which steam, compressed air or other fluid is admitted through flexible conduit connections which are not illustrated. This source of compressed fluid is adapted to be supplied through suitable apparatus connected with a power unit 145 located on the frame 130 and the operator is adapted to occupy a seat 146 from which the various operations of the machine may be controlled. When the bucket is in its lower position shown by full lines in Fig. 7, one cutting edge 135 thereof is arranged to travel along the surface 147 upon which the Caterpillar treads 131 rest.

The sticks 133 on the bucket 135 are adapted to be elevated from the positions shown by full lines in Fig. 7 through the agency of a cable 150 which is attached at one end to a yoke 151 having its arms secured to the pivots 136 of the bucket 135. This cable extends over a pulley 153 mounted on the upper frame structure 132 at one end of the machine and is then carried between sheaves 155 downwardly where it is wound on a drum 156. This drum is adapted to be actuated by suitable power connections extending from the power plant 145 so that the drum may be rotated to raise the sticks 133 about their pivots 134.

In the dotted position shown at 135^a, the bucket has been reversed in position so that it is capable of being loaded when the treads 131 are moved toward the right on the surface 147, as distinguished from the loading action which may be effected by moving the bucket toward the left when it occupies the position shown by full lines in Fig. 7. When the cable 150 is actuated to raise the bucket after it has been loaded, the bucket is first turned to occupy a suspended position so that it will retain its contents and it continues to retain this position as it is elevated to the successive positions which are shown at 135^b, 135^c and 135^d. When the bucket reaches the position shown by dotted lines at 135^e, the sticks 133 are inclined upwardly and toward the right, as viewed in Fig. 7, but the bucket is still suspended to retain its contents and upon further swinging movement of the sticks 133, the cable 150 reverses its position and passes about the pulleys 157 located on the upper right end of the upper frame structure 132, whereupon the sticks are supported from the drum 156 over the pulleys 157, the cable being then wound up on the drum in order to support the sticks in this position. When the sticks have reached the positions shown at 133^a at the right hand side of Fig. 7, the bucket may be inverted in position as shown at 135^f in order to discharge its contents. In this, as in the other forms of the invention, it will be apparent that the contents of the bucket may be discharged gradually by effecting a gradual rotation of the bucket about its axis.

The embodiment of the invention in dragline excavating apparatus is shown in Fig. 8 of the drawings. This apparatus comprises a frame 160 mounted for movement about a vertical axis on a chassis 161 carried by Caterpillar treads 162 which travel on the earth surface shown at 163. 70 75

The operator's cabin is shown at 164 and a boom 165 extends upwardly and toward the right from one end of the frame 160, as shown in Fig. 1, the lower end of this boom being pivoted on bracket 166. The upper end of this boom has pulley 167 over which passes a cable 168 adapted to be connected at its free end to a bucket 17 through the agency of a bracket 171 and a chain connection 172. This bucket is of the double edged variety and may have the form shown in Fig. 1 or the form shown in Figs. 9 and 10 although the form shown in Fig. 1 is preferable. The cable 168, after passing over the pulley 167 is extended downwardly and toward the left into the cabin or housing 164 where it is capable of being wound upon a power actuated drum whereby the bucket 170 may be raised and lowered with respect to the free end of the boom.

The boom 165 may be raised and lowered about 20 the pivot at its lower end through a connector formed by arms 175 which are attached to the other end of the boom at the axis of the pulley 165 and which carry at their inner ends a pulley 176 about which a cable 177 passes. This cable 25 extends into the housing 164 and is adapted to be wound upon a drum by power actuated means so that the position of the boom 165 is determined by the effective length of the stretches of the cable 177 between the drum and the pulley 30 176.

The double-edged cutting bucket 170 is adapted to be actuated automatically in cutting, loading and dumping through the agency of the cable mechanism by which it is manipulated. This 35 cable mechanism includes, in addition to the parts heretofore described, a cable 180 which is attached at one end to an arm 181^a carried by a counterweight 181 secured to one edge of an end wall 170^a of the bucket. This cable extends around a pulley 182 attached to the bracket 171 which is located at the free end of the cable 168 and, after passing over this pulley, the cable extends downwardly and is attached to a bracket 183 comprising a pair of pivoted arms. The pivot 40 45 of these arms is connected through a chain 184 to a connecting member 185 carried by the counterweight 181. When the bucket is suspended as shown by full lines in Fig. 8, one cutting edge 170^b of the bucket is directed downwardly in position to cut along the inclined surface 187^a of the excavation 187.

As the bucket moves downwardly and toward the frame of the machine, during the process of digging and loading, the bucket is adapted to be 50 moved by a cable 190 which extends from one arm of the bracket 183 through sheaves 191 carried by the end of the frame 160, and from these sheaves the cable 190 passes into the housing 164 and is wound on a drum which may be power actuated to draw the cable inwardly toward the housing. When the bucket 170 has reached the position 170^c, it is still in digging position with one cutting edge directed downwardly. Upon reaching this point, the cable 190 is tightened 55 with the result that the bucket is turned and caused to assume the position shown at 170^d where the cutting edge moves along the horizontal surface 187^d. Upon further tightening of the cable 190, the bucket 170 is further turned and caused to assume the position shown at 170^e so that the cutting edge moves upwardly along the inclined surface 187^e. In this position the bucket is loaded and is in readiness to have its contents discharged. During these movements, the position of the bucket has been automatically con-

trolled by the pull upon the cable 180 and by the automatic action of the cable 180 and the chain 184 and, after the bucket has been filled, it may be elevated through the position shown at 170 until it finally reaches the dumping position shown at 170^c, it being caused to assume the latter position, of course, only after the frame 160 has been turned about its vertical axis in order to cause the bucket to occupy a position over the place where it is to be dumped. During these movements, the cables 168 and 190 are operated in order to permit and effect the necessary movements of the bucket and the turning of the bucket is automatically controlled by the cable 180 and the chain 184 which are adjusted to the proper length for the purpose.

In the various forms of the invention which have been described, the source of power which moves the vehicle about on its treads may be used to supply power for operating the various parts by which the bucket is carried and moved and, also, to rotate the bucket. It will be apparent that steam, electric or gasoline power may be used and suitable controlling devices may be mounted on the frame and in the operator's cabin so that the digging, moving, loading and dumping operations may be effected from one position and under the control of a single operator.

Although several forms of the invention have been shown and described by way of illustration, it will be understood that the invention may take various other forms within the scope of the appended claims.

I claim:

1. Excavating apparatus comprising, a bucket having oppositely disposed parallel cutting edges, a frame, means for supporting said bucket from said frame, means for moving said bucket transversely to its cutting edges toward and away from said frame to effect the cutting action of either cutting edge, and power driven means for rotating said bucket about its own axis and holding it in any desired angular position.

2. Excavating apparatus comprising, a bucket having oppositely disposed parallel cutting edges, a frame, means for supporting said bucket from said frame, means for moving said bucket transversely to its cutting edges toward and away from said frame to effect the cutting action of either cutting edge, and power actuated means controlled from said frame for rotating said bucket through a complete revolution about its own axis.

3. Excavating apparatus comprising, a pivoted support, a bucket having oppositely disposed parallel cutting edges, means for mounting said bucket on said support to rotate about an axis extending parallel to said cutting edges, power actuated means for rotating said bucket about its pivotal axis, means connected eccentrically to said bucket for moving said support about its pivot, and means for moving said bucket toward and from said support.

4. Excavating apparatus comprising, a frame, a boom mounted on said frame and projecting therefrom, a bucket having oppositely disposed parallel cutting edges, power actuated means for supporting said bucket from said boom and effecting relative movement of said bucket and said boom, and power actuated means for rotating said bucket about its own axis and controlling the rotation thereof.

5. Excavating apparatus comprising, a frame, a boom mounted on said frame and projected therefrom, a bucket having oppositely disposed parallel cutting edges, means for supporting said

bucket from said boom for rotation about an axis extending parallel to said cutting edges and transversely to said boom, power actuated means for effecting relative movement of said bucket and said boom, and power actuated means for rotating said bucket through any part of a complete revolution about said axis.

6. Excavating apparatus comprising, a frame, a boom mounted on said frame and projecting therefrom, a bucket having oppositely disposed parallel cutting edges, means for supporting said bucket from said boom for rotation about an axis extending parallel to said cutting edges and transversely to said boom, power actuated means for effecting relative movement of said bucket and said boom, power actuated means for moving said bucket toward said frame, and separate power actuated means for rotating said bucket about its axis.

7. Excavating apparatus comprising, a frame, a boom mounted on said frame and projecting therefrom, a bucket having oppositely disposed parallel cutting edges, means for supporting said bucket from said boom for rotation about an axis extending parallel to said cutting edges and transversely to said boom, power actuated means for effecting relative movement of said bucket and said boom, power actuated means for moving said bucket toward said frame, and power actuated means for rotating said bucket about its axis, all of said power actuated means being controlled from said frame.

8. Excavating apparatus comprising a frame, a boom having one end pivotally mounted on said frame for rotation in a vertical plane, said boom projecting from said frame, a dipper stick pivotally connected to the other end of said boom and supported thereby, said dipper stick being rotatable in a vertical plane about its pivotal center, a bucket having a curved bottom plate terminating at two opposite extremities in parallel cutting edges, said bucket also including a pair of spaced end walls secured to said bottom plate and co-operating therewith to define a material-holding cavity, said bucket being pivotally connected to one end of said dipper stick, the pivotal axis of said bucket being parallel to and midway between said cutting edges and parallel to the pivotal axis of said dipper stick, a cable connected to said dipper stick near the end thereof adjacent said bucket, power means carried by said frame and connected to said cable and operative to pull said bucket toward said frame and to rotate said dipper stick in the corresponding direction, a second cable connected to the end of said dipper stick remote from said bucket, and power means carried by said frame and connected to said second cable and operative therethrough to rotate said dipper stick in the opposite direction.

9. Excavating apparatus comprising, a bucket having oppositely disposed cutting edges, a frame, a support for said bucket mounted on said frame, means for moving said bucket transversely to its cutting edges toward and away from said frame to effect the cutting action of either cutting edge, means for mounting said bucket for rotation on said support, and fluid pressure operated means mounted on said support and connected to said bucket eccentrically to the pivotal axis thereof for rotating said bucket and controlling the angular position thereof.

EDWARD H. KLUCKHOHN.
